SAFETY DEVICE FOR DENTAL UNITS

Norman E. Lauterbach, Pittsford, N. Y., assignor to Ritter Company, Inc., Rochester, N. Y., a corporation of Delaware

Application October 20, 1955, Serial No. 541,642

6 Claims. (Cl. 312—209)

This invention relates to an equipment stand and more specifically to stands of the type comprising a unitary column or pedestal for supporting a variety of dental, medical and like equipment within convenient reach of the user adjacent the place of use. Reference is made to Patent No. 2,690,945 issued October 5, 1954 to Fay E. Bronk.

In the equipment stand of the above mentioned patent, an electric motor, through suitable linkage, opens a door or closure and projects the instruments from a position within the equipment stand to a position within convenient reach of the user. When the dentist or physician is through with work on a particular patient, the motor is again actuated to retract the equipment within the equipment stand and close the door to protect the instruments from dust and possible damage when in an exposed position. Notwithstanding the fact that initiation of the operation of the motor is by a switch within the convenient reach of the dentist, it has been found in practice that a dentist will occasionally inadvertently or carelessly endeavor to open or force the door manually to enable access to the instruments. Moreover, it has been found in practice that occasionally one of the instruments may not be fully retracted within the instrument holder when the dentist presses the switch to close the door and the instrument or its cord may be caught between the edge of the door and the margin of the opening in the equipment stand which the door closes. In the mechanism of that patent the connection between the motor and the instrument holder is such that when this occurs the mechanism will become jammed and bent or the motor shaft will be snapped off.

An object of my invention is to overcome the difficulties above set forth with the structure shown in the Bronk patent when the equipment is carelessly operated.

Another object of my invention is to provide in the linkage between the motor and the door and instrument holder, a connection which is automatically broken when an attempt is made to manually force open said door or when an object becomes caught between the edge of the door and the margins of the opening which the door closes.

More specifically, my invention contemplates the employment of a novel toggle construction in the mechanism of the above mentioned patent which will "break" when an undue strain is placed upon the mechanism or the motor is overloaded due to careless or inadvertent operation of the mechanism.

Other objects and advantages of my invention will be pointed out in the claims and will be apparent from the following description, when taken in connection with the accompanying drawings, in which:

Fig. 1 is a view showing the interior of the equipment stand in which the instruments are normally housed, showing the instrument holder retracted and the door in its closed position, the view showing only such portion

2

of the equipment stand with which the invention is concerned;

Fig. 2 is a view similar to Fig. 1 with the holder and the instruments in their projected position and with the door open;

Fig. 3 is a view showing the position of the parts when the connections between the motor and the instrument holder and door are "broken" due to incorrect or careless use of the equipment;

Fig. 4 is a top plan view of a part of the linkage shown in Figs. 1 to 3 inclusive and showing the toggle link which is "broken" when an attempt is made to force the door open manually;

Fig. 5 is a sectional view taken substantially on the line 5—5 of Fig. 4 in the direction indicated by the arrow;

Fig. 6 is a view showing a portion of the linkage and in particular the toggle link of Figs. 4 and 5, the view showing the parts in the position which they occupy when the door is closed and the instrument holder retracted;

Fig. 7 is a view similar to Fig. 6, the links being shown in the position which they occupy when the door is open and the instruments projected;

Fig. 8 is a view similar to Figs. 6 and 7 but showing the position of the parts when the toggle has been broken, the view corresponding to the position of the parts shown in Fig. 3; and

Fig. 9 is a view showing how the toggle link is "re-made" automatically after being broken when the motor is again actuated.

In the drawings I have shown only so much of an equipment stand as is required for the purposes of this invention. However it will be understood that the equipment stand includes a column supported from the floor

which carries a rotary drill and its associated mechanism, a cuspidor bowl, a tumbler holder, an instrument table arm and its associated table and other appurtenances common in the art. All of the elements disclosed in this application and their operation will not be described in detail, reference to the abovementioned patent being had for that purpose.

Referring to Figs. 1 and 2, the equipment stand comprises a housing 11 having an opening 12, and a holder

13 having sockets for the reception of a plurality of dental or medical instruments 14. The stand includes a door 16 and a plurality of retractable cords or cables 17 which enable the individual instruments 14 to be pulled out of their holder and be automatically retracted into the holder when released as is common practice in the art.

The holder 13 is supported for movement to project it forwardly through the opening 12 as will be apparent from comparison of Figs. 1 and 2, opposite sides of the holder having trunnions 18 serving to pivotally connect the holder between spaced arms 19 which are bridged through a portion of their extent by a panel 21. The panel carries certain controls not necessary to describe herein and when the instruments are in extended position as shown in Fig. 2, the panel closes the opening above the holder.

The side walls of the panel 21 have their upper ends extended to provide spaced arms 22 which are pivoted on studs or trunnions 23 which are supported internally of the equipment stand. Arms 22 are extended beyond their pivots 23 to form fingers 24 each having its end connected to a counterbalance spring 26. A second set of springs

27 is connected between the ends of the fingers 24 and stationary parts 28. The operating mechanism includes links 29 pivoted at 31 to the rear end of the holder 13 and at 32 to a frame 33 rigidly supported internally of the housing.

The door 16 is carried by a pair of spaced arms 34

which are pivoted to the frame 33 at 36. The springs 26 are connected to the arms 34 to counterbalance the weight of the cover 16. Each of the arms carries a pair of upstanding elements 37 forming a cam groove 38 in which a roller 39 rides. These rollers 39 are rotatably supported in brackets carried by the arms 29.

The mechanism described is actuated by a motor diagrammatically illustrated at 41. On the end of the motor shaft an actuating element 42 is provided having three arms 43, 44 and 46. Two of these arms 43 and 44 actuate micro-switches while the third arm 46 serves as a crank arm. Reference is made to the above mentioned patent for a disclosure of the motor circuit and its associated parts, it being sufficient to state herein that a manual switch located within convenient reach of the dentist controls the automatic switches to initiate movement of the parts from one position to another that is from the position shown in Fig. 1 to that shown in Fig. 2 or reverse. Upon each actuation of the manual switch the actuator 42 rotates through 180 degrees. The circuit and switches are arranged so that upon actuation of the manual switch and the completion of 180 degrees of rotational operation, motor operation is discontinued. The crank arm 46 is connected by toggle link means, generally indicated by the numeral 47, to the panel 21 as shown at 48. The details of this toggle link means constituted the improvement of my invention and has been shown in Figs. 4 to 9 inclusive.

It is believed that the operation of the mechanism from the foregoing description, particularly upon reference to the above mentioned patent will be understood. When the parts are in the position shown in Fig. 1, a brief closure of the manual switch serves to start the motor and close the automatic switch until the parts reach the projected position of use shown in Fig. 2 at which time the operation of the motor brings about the opening of the circuit and arrests the movement of the parts. Such operation first swings the cover or door to at least a partially open position and swings the holder and panel to the advanced position shown in Fig. 2 in which position the instruments are projected within easy reach of the operator or dentist standing or seated on the opposite side of a dental chair in which a patient is seated. After use of the instruments carried by the holder, a second operation of the manual switch retracts the instrument holder and control panel and completely closes the housing opening to protect the parts, exclude dust and maintain the finish and pleasing appearance of the equipment stand.

As previously mentioned, it has been found in practice that dentists will carelessly or through unfamiliarity with the equipment, operate it improperly. Occasionally a dentist will attempt manually to open the door when the parts are in the position shown in Fig. 1. Any substantial manual force exerted on the door will throw a strain upon the arms 34 and throughout all the links previously described which is likely to bend the links or break the motor shaft. A similar result may occur if the dentist has an instrument in an extended position with respect to the holder and releases the instrument for retraction into the holder while at the same time pressing the manual switch. The instrument may then be jammed between the upper edge of the door and the margin of the opening which it closes, that is, adjacent the point 51 (Fig. 1). Due to the inadvertence or carelessness of dentists in operation of their equipment, it has been found desirable or necessary to provide means for protecting the equipment should it be improperly operated. Such means comprises the toggle link means 47 shown in Figs. 4 to 9 inclusive.

As shown most clearly in Figs. 4 and 5 the toggle link means 47 comprises an arm 52. The arm 52 has a bottom wall 53 and a pair of upstanding sidewalls 54. A pivot rod 56 constituting the pivot 48 (see Figs. 1 and 2) extends through the sidewalls 54. A pivot pin 57 extends through the sidewalls at the opposite end of the

arm 52. The sidewalls 54 are notched as shown at 58 to accommodate a pin 59 mounted on the end of the actuating arm 46. The pin 59 is adapted to pivotally receive a toggle link 61 which lies between the sidewalls 54 of the arm 52 and is pivoted on the pin 57. A spring 62 somewhat S shaped having one end secured to the toggle link, as shown at 63, is confined by a pin 64 extending between the sidewalls 54. The spring retains the toggle link 61 in the position shown in Fig. 5. Adjusting means, shown at 66, determines the position to which the spring 62 will urge the toggle link 61. By threading inward or outward on the adjusting means 66 the effect of the spring 62 may be decreased or increased. Upon threading the adjusting means inward, the toggle may be "broken" more easily.

In Fig. 5 I have drawn two lines A and B. Line A extends through the pin 64 and pivot 57. It will be noted that the point 63 of attachment of the spring to the toggle link lies below this line. Thus the spring retains the toggle link 61 below a dead center position represented by the line A. The line B extends through the center of the pivot rod 56 and through the pivot pin 57. The center of the pin 59 lies slightly above this line B. Thus the force of the motor, rotating the actuating arm 46, tends to break the toggle while the force of the spring 62 overcomes the force of the motor and retains the toggle in the position shown in Fig. 5 unless the motor becomes overloaded by reason, for example, of an instrument or other object being caught between the upper edge of the door and the margin of the door opening. Such overloading of the motor will cause an upward force on the pin 59 and "break" the toggle.

In Fig. 6 I have shown the parts of the toggle link means 47 and its associated parts in the position which they occupy when the door is closed as will be evident from a comparison of Figs. 1 and 6. Likewise I have shown the position of the parts in Fig. 7 when the door is open which will be evident from a comparison of Figs. 2 and 7. In Fig. 8 I have shown the toggle broken. In this position of the parts the load on the motor due to jamming of the mechanism has caused the force exerted by the motor on the pin 59 to overcome the spring 62 and "break" the toggle. The rigid connection between the actuator 46 and the panel 21 is then destroyed to thereby prevent bending of the links or the snapping of the motor shaft. When the toggle has been broken, as illustrated in Fig. 8, due to the lack of a rigid connection between the parts, the door and the instrument holder may drop to the position shown in Fig. 3 and any obstruction may be removed. The entire mechanism is exposed for repair if necessary. With the parts in the position shown in Figs. 3 and 8, the user may again press the manual switch to rotate the actuator 46 through 180 degrees again to form a rigid toggle. The position of the parts just prior to forming the rigid toggle arm or link is shown in Fig. 9.

While I have shown and described the preferred form of my invention it will be apparent that various modifications may be made in the form of relations of parts without departing from the spirit of my invention as set forth in the appended claims.

I claim:

1. In a medical equipment stand the combination of an electric motor and an instrument holder, means interconnecting said motor and holder for projecting the holder from a position within the equipment stand to an external position with respect thereto, means including a manually operated switch for initiating the operation of the motor and a "make" and "break" toggle in said interconnecting means for protecting the motor should it become overloaded, said toggle including two elements pivoted to each other one of which is connected to the motor and the other of which is connected to the holder, a stop between said members, a spring for normally holding one of said members against said stop and in a be-

yond dead center position and means including said motor for throwing said member away from said stop and to the other side of the dead center position should the motor become overloaded.

2. Mechanism of the character described comprising, in combination, motor means, a crank arm driven by said motor means, a pivoted arm adapted to support and swing an object to be shifted from one position to another position upon one cycle of the motor means and returned to its original position upon a succeeding cycle of said motor means, link means pivoted to said arm and having connections to said crank arm which connections include a "make" and "break" toggle, said "make" and "break" toggle comprising a toggle link having a pin which pivotally connects the toggle link to the crank arm, a pivot between said toggle link and said link means, a spring biasing said pin and toggle link into a position such that a driving connection is formed from the motor means to said pivoted arm through said link means during normal operation of the mechanism, the force of said motor means when overloaded overcoming the spring bias to "break" said driving connection which condition of motor means overload may be occasioned by a resistance to the free swinging movement of said arm.

3. Mechanism in accordance with claim 2 in which operation of the motor means is controlled by a switch which upon actuation initiates rotation of the motor means which then rotates through 180 degrees after which the driving force of the motor is discontinued.

4. Mechanism in accordance with claim 2 in which the pivot connection of said link means and the pivot connection of said toggle link to said link means form a

line and the spring normally biases the toggle link to a position on one side of said line while the rotational force of the motor means tends to move the toggle link to the other side of said line, the force of said spring being sufficient to overcome the torque of the motor means under normal conditions of operation but insufficient to overcome the force of the spring should an overload be imposed upon the motor means.

5. Mechanism in accordance with claim 2 in which the pivot connection of said link means and the pivot connection of said toggle link to said link means form a line and the spring normally biases the toggle link to a position on one side of said line while the rotational force of the motor means tends to move the toggle link to the other side of said line, the force of said spring means being sufficient to overcome the torque of the motor means under normal conditions of operation but being sufficient to overcome the force of the spring should an overload be imposed upon the motor means and means for adjusting the position to which said spring biases said toggle link on the first mentioned side of said line.

6. Mechanism in accordance with claim 2 in which means are provided for "making" said toggle upon the next cycle of said motor means if the resistance to the free movement of said arm has been removed.
